UNITED STATES PATENT OFFICE.

CHARLES R. SARGENT, OF GRAND RAPIDS, MICHIGAN.

CLOTHES-BASKET.

1,173,746.

Specification of Letters Patent. Patented Feb. 29, 1916.

Application filed March 11, 1912. Serial No. 683,025.

To all whom it may concern:

Be it known that I, CHARLES R. SARGENT, a citizen of the United States of America, residing at Grand Rapids, in the county of Kent and State of Michigan, have invented 5 certain new and useful Improvements in Clothes-Baskets; and I do hereby declare the following to be a full, clear, and exact description of the invention, such as will 10 enable others skilled in the art to which it appertains to make and use the same.

My invention relates to improvements in baskets and more particularly to clothes baskets and the like and its object is to provide 15 a more convenient device, to provide the same with supporting means whereby it is more convenient for use, to provide the same with folding legs and automatic means for operating the said legs and to provide 20 the device with various new and useful features hereinafter more fully described and particularly pointed out in the claims.

Heretofore clothes baskets have been made adapted to be deposited on the floor or 25 ground or requiring some table or other suitable support to elevate the same in the event that it was found convenient so to do.

My invention consists essentially of a 30 clothes basket of any convenient construction provided with folding legs adapted to support the same in elevated position, or to fold closely beneath the same and devices whereby the legs are automatically folded and manually opened adapted to be operated 35 from a position near the top of the basket whereby the basket can be supported and the legs opened at the same time, as will more fully appear by reference to the accompanying drawings, in which:

40 Figure 1 is a perspective view of a basket provided with my invention; Fig. 2 an inverted plan view of the same with the legs folded; Fig. 3 a detail partially in side elevation and partially in section with one pair 45 of legs folded and the other pair partially broken away; Fig. 4 is an enlarged detail in vertical section showing the locking means for holding the legs in open position; Fig. 5 a detail of the same in plan view 50 with parts broken away; Fig. 6 a detail showing an inverted plan of a modification; Fig. 7 the same shown partially in vertical section with one corner of the basket shown in elevation; and Fig. 8 an enlarged detail 55 showing the arrangement of the modified spring.

Like numbers refer to like parts in all of the figures.

1 represents a clothes basket of any convenient construction with the handles 60 omitted.

2 is a frame upon which the basket is supported and to which it is attached in any convenient manner.

3 represents legs attached to the frame 2 65 by suitable hinges 4 said legs being arranged in pairs under the respective ends of the frame and the members of each pair connected by a rod 5. To each rod is secured one end of a contractile spring 6 the other 70 end being suitably anchored beneath the basket. This spring automatically folds each pair of legs close beneath the platform when free to do so. To open the legs out in operative position, a cord 8 is connected to 75 the legs preferably by a wheel 7 on which the cord is wound, from which wheel the cord extends upward across the end of the frame and preferably attached thereto is a rod 8^a slidable in guides 9 and 9^a on the end 80 of the basket the upper guide having clearance enough around the rod whereby a collar or stop 11 will pass through the guide and rest on the top of the same, thus holding the rod 8^a in elevated position and the 85 legs 3 in supporting position with the spring 6 under tension. When the stop 11 is released the legs are automatically folded by the action of the spring 6.

The upper end of each rod is preferably 90 provided with an eye or handle 10 for convenience in manually operating the same. In the modified structure the rod 5^a serves as a means of pivoting the legs to the basket 95 and journaled in lugs 12 on the under side of the frame 2 the spring 6^a being coiled around the rod and secured thereto at one end and to the frame at the other end. This spring serves the same purpose as the 100 spring 6.

On the middle of the rod is a pinion 13 in place of the wheel 7 and a rack 14 engages the pinion and is operated by a rod 8^b which extends upward the same as the rod 8^a and 105 is provided with the same stop 11 and a handle 10 as is rod 8^a.

The operation of the device will be readily understood from the foregoing description.

When the basket is to be used, by seizing 110 the handles 10 and lifting the basket the

handles will move upward relative to the basket and thus the legs will be turned to supporting position as the basket rises, and by engaging the stops 11 with the guides 9^a the legs will be held in this position. To close the legs the stops 11 are released from the loops and the basket lifted by any suitable handles thereon or by the upper band thereof to relieve the legs 3 from the load.

10 The springs 6 or 6^a as the case may be, will then automatically fold the legs beneath the basket. The basket can thus be used in elevated position for filling or emptying the same, and when out of use the legs can be folded closely beneath the same adapting the device to be conveniently stored when out of use.

I have shown herein and described a clothes basket as the element comprising the receptacle of the combination but obviously any other receptacle whatever in place of the clothes basket, such for instance as a wash tub, bath tub or the like would obviously in no wise depart from the spirit of my invention and would be within the scope of what I claim.

What I claim is:—

1. In combination with a basket, legs pivotally connected to the basket and adapted to fold beneath the same and to turn to supporting position, handles at the respective ends of the basket and vertically movable relative thereto, means for connecting the handles and legs whereby the legs are turned to supporting position by raising the handles, means for detachably holding the handles in said raised position, and means for automatically folding the legs when said handles are detached.
2. In combination with a basket, legs pivotally connected to the basket and adapted to fold beneath the same and to turn to supporting position, springs connected to the legs to automatically turn the same to folded position, handles vertically movable relative to the basket, cords connected to the handles and legs whereby the legs are turned to supporting position by moving the handles upward and means for detachably securing the handles in raised position.

Copies of this patent may be obtained for five cents each, by addressing the "Commissioner of Patents, Washington, D. C."

3. In combination with a basket, legs pivotally connected to the basket and adapted to fold beneath the same and to turn to supporting position, springs to automatically fold the legs, cords attached to the legs to turn the same to supporting position and vertically movable handles attached to the cords whereby the basket may be supported and the legs so turned by raising the handles.

4. In combination with a basket, a frame supporting the basket, legs pivoted to the respective ends of the frame and foldable beneath the same, springs connected to the legs to automatically fold the same, manually operated means connected to the legs to unfold the same, extending upward at the respective ends of the basket, and means for locking the legs in unfolded position.

5. In combination with a basket, legs pivotally connected to the basket and connected in pairs by rods, contractile springs connected to the rods at one end and anchored beneath the basket at the other end, a cord connected to each rod and extending upward at the respective end of the basket, a rod attached to each cord and having an eye or handle at the upper end and a stop on each rod adapted to hold the rod in elevated position with the legs in supporting position.

6. In combination with a basket, a frame supporting the basket, a pair of legs pivoted to each end of the frame, a rod connecting each pair of legs, a contractile spring attached to each rod and anchored beneath the basket, a wheel on each rod, a cord wound on each wheel, a rod attached to each cord and extending upward, guides in which each rod is slidable, a loop or handle on the upper end of each rod and a stop on each rod adapted to pass through the upper guide and engage the same to hold the rod in elevated position with the legs in supporting position.

In testimony whereof I affix my signature in presence of two witnesses.

CHARLES R. SARGENT.
